UNITED STATES PATENT OFFICE.

LEONARD A. YOUNG, OF HIGHLAND PARK, MICHIGAN.

SHEATHING OF SPOKES.

1,165,056.

Specification of Letters Patent. Patented Dec. 21, 1915.

Application filed March 15, 1915. Serial No. 14,474.

To all whom it may concern:

Be it known that I, LEONARD A. YOUNG, a citizen of the United States, residing at Highland Park, county of Wayne, State of Michigan, have invented a certain new and useful Improvement in Sheathing of Spokes, and declare the following to be a full, clear, and exact description of the same, such as will enable other skilled in the art to which it pertains to make and use the same, reference being had to the accompanying drawings, which form a part of this specification.

This invention relates to a method and machine for sheathing vehicle wheel spokes. The spokes are made up of wood provided with a sheathing which is placed upon the spoke by a method adapted to secure a very tight fit and to embed the seams in the substance of the wooden spoke itself so that they will not protrude in the finished product. The method is such that not only is the sheathing placed upon the spokes very tightly but the operations may be carried out very rapidly.

The essential steps of my method and the details of the machine will more fully appear in the description hereinafter following.

In the drawings, Figure 1 is a plan view of a machine capable of carrying out my method. Fig. 2 is a vertical section of the machine. Fig. 3 is a cross section of a finished spoke having a lap seam sheathing. Fig. 4 is a cross section of a finished spoke having a lock seam sheathing.

The type of wheel in which the spokes that I make by my new method are used is shown in my Patent 1,125,627, and also in my pending application #7,579, the latter of which is my preferred form of spoke. It will be noted that the spoke is preferably slightly tapering from the hub end *a* to the rim end. This is the customary shaped spoke used in the so called artillery wheels, but instead of making it of very hard wood such as hickory, I make it of a slightly softer and cheaper wood such as maple, which is made possible by reason of the use of the metal sheathing which adds strength to the spoke which otherwise would not be as strong as one made of hickory.

The sheathings *b* are preferably assembled before they are put in the dies, that is to say, the two halves of such a sheathing as is shown in Figs. 3 and 4 are put together before the sheathing is placed in the

machine. The lap seam sheathing of Fig. 3 is welded together at the seams while the lock seam sheathing shown in Fig. 4 does not require welding but the two halved portions may be caused to engage to lock the same together. I do not desire to limit myself to any particular form of sheathing as the same might be made with only one seam, or may be tubing for that matter, provided that suitable tubing could be had for this purpose.

c represents the bed of the machine which is provided in its upper surface with a large wedge-shaped recess *d* in which the two die blocks *e*, *e* run. They are guided in their opening and closing movements by the bolts *f* that pass through the slots *g* in the blocks. Hence when the die blocks *e* are pushed to the left, in Fig. 1, they are constrained to open up. This pushing is effected by the pivoted hand lever *h* which is connected by two links *i* to the tapered ends of the blocks. Consequently by pulling this hand lever *h* to the right as shown by the dotted lines of Fig. 1, the die blocks are opened up. The sheathing *b* may be inserted therein and the die blocks closed again. The next step is to force the spoke into the sheathing in the die blocks by an end to end movement. This is accomplished in the following manner: A spoke is placed in the spreadable sectional guide *u* which comprises a pair of grooved members that are normally yieldingly projected toward each other by the springs *j*. The spreading and contracting movements of the two sets of grooved members of the guide are guided by a plurality of pins *k* fastened to each section of the guide members and capable of reciprocating in the cylindrical recesses *l* in the table bed. The ends of the guide sections toward the end from which the spoke is inserted are divergent as indicated at *m*. The divergence substantially corresponds with the enlargement of the hub end of the spoke.

When the spoke has been inserted between the two sets of yielding members *u* of the guide, it is pushed endwise into the sheathing in the dies by means of the ram or bulldozer *n* which is here shown in the form of a rack slidale in a suitable guide *o* although it is, of course, apparent that other ways of propelling the ram or bulldozer may be employed. The rack engages with the pinion *p* on the shaft *q*. Hence when the shaft is rotated by the application of

power to the pulley wheel r , the ram or bulldozer is quickly driven against the spoke and follows the spoke into the guide and firmly presses the spoke into the sheathing in the dies. 5 The ram or bulldozer is withdrawn by application of power to the shaft q from the other pulley wheel s , which is driven in the reverse direction. This alternate application of power to the two pulley wheels is effected by the clutch t which is built so that the pulley wheels may slip on this when too great resistance is encountered as when the spoke is driven completely home into the sheathing and the dies. 10 It will be noted that the arrangement of the dies is such as to resist the thrust of the spoke to the best possible advantage, as when the dies are together, they are completely wedged between the powerful bosses 15 on the machine bed which surround the tapered recess d . Consequently the resistance to the thrust of the ram or bulldozer is ample to withstand the same. The object in having the two sets of grooved members of the guide yieldingly separable is to 20 allow the passage of the enlarged hub end a of the spoke, which as it passes through the guide sections, spreads the same. 25

From the above description of my method, 30 it will readily be understood that the sheathing is very tightly fitted upon the spoke and yet, while it is being tightly fitted upon the spoke, it is given such external pressure that the seams will not separate nor the sheathing be split by reason of the very heavy internal pressure suffered by the wedging action of the tapered spoke being driven into the tapered sheathing. 35 This external resistance afforded by the dies

also serves to drive the seams as shown in 40 Figs. 3 and 4, directly into the substance of the spoke so that not only does this tighten the fit and securely lock the sheathing to the wooden spoke, but it also prevents the seams from protruding at the 45 sides of the spoke in an inartistic way.

By the method above described and the machine above set forth, the spokes may be ensheathed very rapidly, as a pile of sheathings may be placed adjacent the machine, 50 then one sheathing laid into the dies, the dies closed, a spoke laid into the guide, the power applied and the spoke driven home. The dies may be opened, the completed spoke taken out and the operation repeated, 55 and so on.

What I claim is:

1. A method of sheathing spokes, comprising the driving of a spoke endwise into a sheathing and externally resisting the 60 tendency of the sheathing to expand.
2. A method of sheathing tapered spokes, comprising the driving of the spoke endwise into a tapered sheathing arranged to fit the same and externally resisting the 65 tendency of the sheathing to expand.
3. A method of sheathing tapered spokes, comprising the guiding and driving of the tapered spoke into the tapered sheathing which is arranged to fit the same, and externally resisting the tendency of the sheath- 70 ing to expand.

In testimony whereof, I sign this specification in the presence of two witnesses.

LEONARD A. YOUNG.
